UNITED STATES PATENT OFFICE.

JOSEPH HILL, OF TORONTO, ONTARIO, CANADA.

INTERNAL-COMBUSTION ENGINE.

1,265,913.

Specification of Letters Patent.

Patented May 14, 1918.

Application filed August 10, 1917. Serial No. 185,448.

To all whom it may concern:

Be it known that I, JOSEPH HILL, a subject of the King of Great Britain, residing in the city of Toronto, county of York, 5 Province of Ontario, Canada, have invented certain new and useful Improvements in Internal-Combustion Engines, of which the following is a specification.

My invention relates to improvements in 10 internal combustion engines, and more particularly to that class of engines, known as a double-acting cylinder type, and the objects of my invention are, first, to provide a combustion chamber common to each end of 15 two or more cylinders in which it is only necessary to mount one igniting means for the said cylinders, and secondly to provide means whereby the amount of power developed by the engine can be altered at will 20 without having to stop the engine.

In the following specification, and in the drawings forming part thereof, I show the preferred construction for the embodiment of my invention, though the cylinders and 25 combustion chambers are merely conventional. While I prefer to make my cylinders air-cooled, it will be understood that these parts may be provided with water-jackets if desired.

30 Figure 1 is an elevation of the major portion of a pair of cylinders, with the valves et cetera, showing a vertical longitudinal section through one of the combustion chambers. Fig. 2 is a vertical cross section on the line 2—2, Fig. 1, certain parts being 35 shown in elevation. Fig. 3 is a view of a certain operating element hereinafter referred to, and Fig. 4 is an elevation of the left-hand side of Fig. 2, showing the pair 40 of cylinders carried by a suitable mounting.

In the drawings, like characters of reference refer to the same parts.

45 A are a pair of suitable cylinders suitably associated, and operating within each of these cylinders is a double-headed piston B. These pistons are suitably coupled together and to a connecting rod *a*, by the wrist-pin C, (Fig. 2). Supported at each end of each of the said cylinders is an offset 50 combustion chamber D. These combustion chambers have communication with the cylinders A by means of the ports E. Formed in the lower portion of each combustion chamber D, and separated therefrom 55 by a longitudinal wall F, are a plurality of chambers G which are separated from each

other by walls H. I are intake valves controlling the ports J between the chambers G and combustion chamber D. K is an exhaust valve controlling an exhaust port L 60 between the central auxiliary exhaust chamber G, and the combustion chamber D. M is the usual cam-shaft journaled in suitable bearings N, and this cam-shaft is provided with cams O suitably positioned so that the 65 valves I and K, in each of the combustion chambers D will be timed to operate in proper sequence. The explosive mixture may be conveyed from the carburetor (not shown), by any suitable means. My preferred means comprises the manifold P, the branches of which lead to the chambers G exit from which is controlled by the valves I. Mounted in each combustion chamber D is any suitable igniting means for the explosive mixture. For purposes of illustration, 70 I show an electric igniter 2. These electric igniters will ignite the charge in the explosive chambers D, so as to develop power within the cylinders A, at the required ends, 75 and I am therefore enabled to dispense with a number of igniters now necessarily employed.

It will of course be understood that the pair of pistons B functionate together, and 80 by having the common combustion chamber, I insure that each cylinder A receives its proper proportion of explosive mixture.

Another advantage derived from my invention is that igniter troubles are greatly 85 reduced.

3 is the exhaust port opening from the central auxiliary exhaust chamber G.

In case I should desire to develop power in only one end of the cylinders A, I will 90 make use of means to hold one of the exhaust valves K open; the preferred means for this purpose is as follows: 4 is a rod 95 mounted to move longitudinally in suitable brackets 5 carried by a plate 6 suitably carried by said cylinders A. Journaled between the ears 7, carried by the plate 6, by the pin 8, is a bell-crank lever 9, one arm 10 of which is in contact with the lower end of the stem 11, of the valve K. The other 100 arm 12 of said bell-crank lever is positioned between the rod 4 and the plate 6. To hold the upper valve K, for instance, open, the rod 4 is pushed in the direction indicated by arrow in Fig. 1, and by reason of the cam-face 13 carried thereby, the arm 12 will 105 move toward the plate 6, thus permitting the 110

elevation of the arm 10 and so hold the valve K open. 14 is a stop carried by the rod 4 to limit movement thereof.

The plate 6 is shaped to allow of the necessary movement of the arm 12, since to make these parts compact, it is preferable to have the arm 12 operating close to the plate 6.

When the valve K is held open as described, suitable valves *b*, in the required branches of the manifold P are closed.

While I have described what I consider to be the best embodiments of my invention, still I desire it to be understood that the principle may be embodied in many different forms, and I desire not to be restricted beyond the terms of my claims and requirements of the prior art.

Claims:

- 20 1. The combination with a pair of double-acting cylinders, a double-headed piston mounted in each of the said cylinders, and means whereby said pistons are connected together, of a combustion chamber at each 25 end of the said cylinders, provided with ports opening into said cylinders; a port-provided wall extending longitudinally of said combustion chamber; two vertical walls connecting said longitudinal wall with the 30 lower wall of said combustion chamber thus forming three aligned port-provided chambers beneath said longitudinal wall; the two outer chambers receiving the fresh charges and the intermediate chamber receiving the 35 exhaust; a puppet valve operating through each of the said chambers and controlling the ports in said longitudinal wall; means for operating said valves, and unitary igniting means for said combustion chamber.
- 40 2. The combination of a pair of double-acting cylinders, a double headed piston mounted in each of the said cylinders, means whereby said pistons are connected together; a combustion chamber at each end of the 45 said cylinders provided with ports opening into said cylinders; and each further provided with two intake and one exhaust port-provided chambers separated therefrom by

a wall; intake valves for said intake chambers; means for operating same; an exhaust 50 valve for said exhaust chamber; and means brought into contact with the stem of one of said exhaust valves whereby the said valve can be held open for the purpose specified.

3. The combination of a pair of double-acting cylinders, a double-headed piston mounted in each of the said cylinders, means whereby said pistons are connected together; a combustion chamber at each end of the said cylinders provided with ports opening 60 into said cylinders; and each further provided with two intake and one exhaust port-provided chambers separated therefrom by a wall; intake valves for said intake chambers; means for operating same, an exhaust 65 valve for said exhaust chamber; and means brought into contact with the stem of one of said exhaust valves whereby the said valve can be held open for the purpose specified, comprising a bell-crank lever, one arm of 70 which projects underneath the stem of one of said exhaust valves; means whereby said bell-crank lever is pivoted in place, and a push-rod provided with a cam-surface, carried by said plate and in such position as to 75 operate against said bell-crank lever to hold the designated exhaust valve open.

4. The combination of a pair of double-acting cylinders and a combustion chamber at each end thereof and offset therefrom and 80 provided with ports opening thereinto; a wall extending longitudinally of said combustion chambers and provided with three aligned ports; a vertical wall positioned between each two of the said aligned ports and 85 connecting said longitudinal wall with the bottom wall of said combustion chambers, thus dividing the portion of the said combustion chambers underneath said longitudinal wall into three port-provided chambers, the outer ones of which receive the 90 fresh charges, and the intermediate one receiving the exhaust.

JOSEPH HILL.
